THREAD CUTTER FOR SEWING MACHINES

Filed Oct. 16, 1926

INVENTOR
C. Jebb.
BY J. Edward Markee
ATTY.

UNITED STATES PATENT OFFICE.

CLARA JEBB, OF ORILLIA, ONTARIO, CANADA.

THREAD CUTTER FOR SEWING MACHINES.

Application filed October 16, 1926. Serial No. 142,116.

This invention relates to thread cutters and more particularly to those carried by the presser-foot of a sewing machine, and my object is to provide the presser-foot with simple cutting means which is so located that it may be readily reached by the operator and which is so formed that there will be no danger of the operator nor the work being cut or caught thereby.

10 I attain my object by providing the foot section of the presser-foot with a cutting edge. This is formed by making a notch in the vertical edge of the foot section whereby the cutting edge lies behind the plane of the said vertical edge and in the plane of the upper surface of the foot section.

15 The constructions are hereinafter more fully described and illustrated in the accompanying drawings in which

Fig. 1 is a diagrammatic view of parts of a sewing machine showing the position of the bobbin and the needle thread across the cutting edge on the presser-foot;

20 Fig. 2 a plan view of the presser-foot;

Fig. 3 a side elevation thereof; and

Fig. 4 a cross section on the line 4—4 in Fig. 2.

In the drawings like numerals of reference indicate corresponding parts in the different figures.

1 is a presser-foot which is carried in any suitable manner on the presser-foot bar 2 and is provided with the usual foot section 1^a. This section is provided with an opening 3 for the passage of the needle 4 and is substantially rectangular in cross section as usual.

20 A cutting edge 5 is provided by forming a notch in a vertical edge 1^b of the foot section 1^a. The cutting edge is thus located behind the plane of the vertical edge and in or below the plane of the upper surface of the foot section. From this it is obvious 45 that the cutting edge is well out of the way of the operator's fingers and the work being sewn so that there is no danger of their being cut.

It will also be noted that in my thread cutter there are no projections of any kind 50 that are liable to catch the work which makes it possible to locate the cutting edge in the most accessible position.

To provide a bevelled cutting edge the notch in the vertical edge 1^b of the presser 55 foot is undercut.

The mode of operation is as follows. When it is desired to cut the threads 6 and 7 from the needle 4 and the bobbin (not shown), the presser foot and the needle are raised in the usual manner and the work 60 is drawn to one side thereof as shown in Fig. 1. While doing this the operator grasps both threads at *a* by the left hand and, when sufficient thread has been drawn from the needle and the bobbin supply, both threads are grasped by the right hand at *b*. The portions *a* to *b* of the threads are then carried to a position above the presser-foot and preferably in alinement 70 with the cutting edge 5 so that the threads will be cut when they are moved downwardly into contact with the cutting edge. The notch also serves as a guide to direct the threads to the cutting edge should they be 75 drawn along the edge 1^b.

What I claim is:

A presser foot having its outer side forward of the needle opening of the foot meeting the upper surface substantially at right angles thereto, the said side adjacent its forward end having a notch cut therein sloping in a downward and inward direction to form a bevelled cutting edge at the upper surface of the foot, the said cutting edge forming an indentation in the outer edge of the upper surface of the foot, whereby threads may be cut by drawing them downwardly and transversely against the cutting edge.

Signed at Orillia this 30th day of September 1926.

CLARA JEBB.
